UNITED STATES PATENT OFFICE.

PETER E. KROEHLER, OF NAPERVILLE, ILLINOIS.

FOLDING-SEAT DAVENPORT.

1,145,071.

Specification of Letters Patent.

Patented July 6, 1915.

Application filed January 30, 1912. Serial No. 674,323.

To all whom it may concern:

Be it known that I, PETER E. KROEHLER, a citizen of the United States, and a resident of the city of Naperville, in the county of DuPage and State of Illinois, have invented certain new and useful Improvements in Folding-Seat Davenports; and I do hereby declare that the following is a full, clear, and exact description of the same, reference being had to the accompanying drawings, and to the numbers of reference marked thereon, which form a part of this specification.

Of the various types of davenports heretofore constructed, difficulty has been experienced in affording a suitably compact construction to enable the bedding to be folded and contained within the device without necessitating the elevation of the seat to an extent to render the device uncomfortable for day use. This object has been accomplished to a greater or less extent in full-length davenports, or those in which the davenport frame is of sufficient length to necessitate but a single fold of the mattress, but even in these it has been exceedingly difficult to afford the necessary storage space for the bedding without rendering the device clumsy in appearance and uncomfortable in use. The difficulty, of course, becomes vastly greater with comparatively short davenports or divans, in which the mattress is folded a number of times in closing, and in which, when opened, the mattress is extended forwardly from the davenport for approximately bed length.

In the devices for the purpose, as heretofore constructed, the construction has frequently proven defective to an extent as to render the device exceedingly short-lived and sometimes uncomfortable when in use.

The object of this invention is to afford a davenport of the class described adapted to be extended at a right angle with the length of the davenport frame and to a sufficient extent as to afford a bed of the desired length.

It is also an object of the invention to afford a construction in which the bed frame or mattress frame, when extended, possesses great rigidity and strength, and is so constructed as to support the weight of the occupants without tendency to sagging or springing out of alignment.

It is a further object of the invention to afford a construction in which the mattress folds downwardly within the davenport

frame, and is positively supported and suspended therein when in place, with the seat at a proper height for most convenient use.

It is also an object of the invention to afford a davenport bed of the class described in which the mattress is adapted to be folded a plurality of times, and to be wholly contained within the davenport frame below the normal plane of the seat when in place.

It is also an object of the invention to afford a spring suspension in connection with a device such as described, by the use of which the inward folding of the mattress is balanced to prevent shock and jar in closing the mattress, and in which the weight of the mattress and bed frame is yieldingly supported to assist in elevating the bed frame and mattress into operative position when extended for bed use.

It is a further object of the invention to afford a construction in which the mattress and bed frame are foldable wholly within the davenport frame well below the seat level when not in use, and when in use are elevated to a point approximately coincident with, or above the normal seat level.

It is also an object of the invention to afford a receptacle for pillows and extra bedding within the davenport seat, and wherein the same are confined by the collapsing of the bed frame thereupon when the device is closed.

The invention embraces many novel features and (in a preferred form) is illustrated in the drawings and hereinafter more fully described.

In the drawings: Figure 1 is a fragmentary top plan view of a device embodying my invention, showing the back of the davenport frame broken away to illustrate the spring suspension. Fig. 2 is an enlarged end elevation, with the end of the davenport broken away, and the davenport closed. Fig. 3 is a similar view, showing the davenport partly opened. Fig. 4 is a reduced view, illustrating the further opening of the davenport. Fig. 5 is a similar view, showing the davenport fully opened. Fig. 6 is a section taken through the seat and mattress frame, and showing the seat inverted. Fig. 7 is an enlarged, fragmentary perspective view illustrating the toggle connection and joint for the first fold of the bed and mattress. Fig. 8 is an enlarged fragmentary detail view of the construction for supporting the inverted seat and third

section of the mattress frame. Fig. 9 is an enlarged, fragmentary detail of the locking means for engaging the three outer sections of the mattress frame in folded relation. 5 Fig. 10 is an enlarged fragmentary detail, illustrating the latch, whereby the davenport seat is engaged closed. Fig. 11 is a fragmentary side elevation of the same.

As shown in the drawings: the davenport 10 frame comprises arms or end members 1, a relatively low front wall 2, and a back wall 3, a back wall 4, connecting the end members 1, and upholstered above the seat to afford the back of the davenport. Said side and 15 end walls afford a box, into which the bed of the davenport folds and into which the seat frame 5, fits when the davenport is closed. The lower edges of the box or frame extend in close proximity to the floor, 20 and are supported therefrom by means of suitable casters to afford suitable clearance.

The metallic bed frame is constructed in a, plurality of foldable sections, and, for this purpose, a main frame section 6, is articulated 25 with a short folding section 7, which at its outer end, articulates with a longer frame section 8, with which is connected a short folding section 9, the outer ends of which are connected again with a longer 30 section 10, said sections being so articulated together as to permit the same to roll inwardly one upon another until the bed frame and mattress are rolled into small compass, as shown in Fig. 2, and deposited 35 within the box affording a part of the davenport.

As shown, the sections are constructed of angle bars suitably connected at the corners to afford a rigid frame, and the short sections 40 7, connecting the longer frame sections 6 and 8, articulate with the ends of said frame sections respectively, and the short sections 9, articulate at their ends respectively with the ends of the frame sections 8 45 and 10. The bed frame thus constructed may be covered with any suitable spring mattress fabric, the construction illustrated in Fig. 1, being intended to illustrate merely a conventional spring fabric.

50 Extending upwardly from each of the forward corners of the frame box of the davenport, is a bracket 11, which curves upwardly and slightly outwardly, and pivotally connected on an arm 12 thereof, which 55 extends rearwardly along the end of the davenport, is an upwardly, rearwardly extending link or arm 13, the other end of which is pivotally connected with the bed frame section 6. Said link on its forward 60 side is bent or shaped to afford an upwardly extending angle or projection, and pivotally connected thereon at one of its ends, is a link or toggle bar 14, the other end of which is pivotally engaged upon a rigid bracket 65 15, rigidly secured upon the under side of

the frame of the seat 5. As shown also, a link or toggle bar 16, connects the upper forwardly projecting extremity of the bracket 11, with the base of the bracket 15, at the forward lower edge of the seat frame. 70

The bed frame section 7, is pivotally engaged near its middle on the upper extremities of the seat frame bracket 15, and the ends of the webs of said section 7, overlap the webs of the sections 6 and 8 respectively, 75 to hold the same in rigid alinement when extended, as shown in Fig. 7, but permitting the same to fold up readily, as illustrated in Figs. 2 and 3.

Means are provided to support the forwardly turned back edge of the seat frame upon the floor, and to support the bed section 8, thereon. For this purpose, as shown, a leg 18, is pivotally engaged at each end near the rear side of the seat frame to be 80 projected downwardly to the floor when over-turned, as illustrated in Figs. 4 and 5.

Journaled at each end of the seat frame at the under side and near the middle of the end frame member for the seat frame, is a 90 short shaft 19, having an arm 20, secured on each end thereof, on each side the end seat frame member, and projecting normally toward the upholstered cushion of the seat. At the outer side of the end frame member 95 of the seat, a toggle bar 21, connects said arm 20, with the leg 18, at a point sufficiently distant from the pivot of the leg, to cause the leg to be actuated by the movement of said arm. The other of said arms 20, is 100 pivotally engaged at its end by one end of the link or toggle bar 22, the other end of said toggle bar 22, engages a link 23, or swinging standard, pivoted at its lower end on the seat frame and on its upper end pivotally engaged somewhat outwardly from the center of the bed frame members 8. 105

A bent brace bar 24, (which may be tubular, if desired) extends transversely the bed frame and is pivotally engaged at its ends 110 near the middle of each of the frame sections 9, and a link 25, is pivotally engaged on each of the extended ends of said brace bar, or is otherwise suitably pivoted near the middle of said frame section 9, as shown in 115 Figs. 4 and 5, and at the opposite end pivotally engages the upper end of a leg 26, which is pivoted near its upper end on the outer end of the bed frame section 10.

Rigidly secured on each leg 26, closely adjacent its pivotal connection with the bed frame members 10, are inwardly projecting latch arms 27, each having a notch or hook in the free extremity thereof and of a length to close upon and engage a suitable pin or lateral projection 28, on the respective bed frame bars 8, as shown more plainly in Fig. 3, when the bed frame is folded up, thereby serving to lock the bed frame with the bed 125 folded therein, in closed relation. 130

Secured at one end on suitable brackets 29, secured in the angle afforded by the back and end frame members of the davenport frame, are strong pulling springs 30, the other ends of which extend forwardly and engage the inner end of the bed frame member 6. Said springs are so disposed as to exert tension on the bed frame when the bed is wholly elevated and extended for use, and also to exert strong sustaining and supporting tension as the bed when folded, is being lowered into the bottom of the davenport frame. For this purpose, the connection of the ends of said spring, with the back and ends of the davenport frame, are but slightly below the plane of the bed frame when extended. In consequence, said springs at all times tend to lift the folded bed frame and mattress from the box or frame therefor, thus tending to balance the weight thereof in opening or handling the same. As shown also, a latch is provided at the rear side of the davenport seat comprising a spring 31, carrying at its outer upper end a transverse bar or rod 32, adapted when the seat is closed inwardly, as shown in Fig. 2, to engage beneath the upholstered back of the davenport. A suitable loop 34, of any suitable material, is secured to the seat 5, and extends over the bow of the latch and is adapted to be used to pull said spring and rod inwardly to unlatch the seat in opening the bed.

As shown, the seat frame is open on its under side to afford a box or compartment to receive extra bedding and pillows. Owing to this construction, when the bed is fully extended, as shown in Fig. 5, sufficient space is afforded between the bottom of the seat frame and the extended bed frame, to permit the ready removal of such extra bedding or pillows, indicated by X and Y in Fig. 6, or the same may be readily removed or inserted when the bed is partly opened, as illustrated in Fig. 3. When, however, the bed is closed as illustrated in Fig. 2, the section 8, of the bed frame folds partly within the box afforded by the seat frame, thus confining the bedding in place, as shown by dotted lines in Fig. 2.

The operation is as follows: When the bed is closed, as shown in Fig. 2, the seat is first unlatched by pulling upon the loop 34, thus retracting the latch and permitting the bottom to swing upwardly and forwardly, as shown in Fig. 3. This is materially assisted, as shown in Fig. 3, by the upward draft of the spring 30, which serves to balance the bed frame and the bedding, enabling the same to be handled with very little exertion. When the seat is swung down to the position shown in Fig. 4, the latches 27 are released from their engagement on the studs 28, of the sections 8, and the end section 9, 10 of the bed is swung forwardly and downwardly, as

shown in Figs. 4 and 5, such downward movement causing the leg 26 to swing forwardly, as shown in Fig. 5, to supporting position. The downward movement of the seat portion of the davenport causes the leg 18, to move downwardly to supporting position, as shown in Fig. 4. This is occasioned by the relative movement of the bed frame on the toggle bars and brackets, on which the bed frame is supported upon the davenport frame and seat frame, it being obvious from the construction described, that as the seat frame swings downwardly to horizontal position, using the link 16, as a fulcrum, the bed frame is drawn outwardly and elevated, the cross connection between the bracket 15, and the bracket or lever 13, by means of the toggle bar or link 14, serving also to elevate and support the inner bed section 6, as shown in Fig. 3, and affording an exceedingly strong and rigid support therefor.

The outer bed frame section 9, is now turned downwardly, inasmuch as the link 25, is connected near the middle of the short frame section 9, such downward folding of the outer end of the bed frame swinging the leg 26, downwardly, thus supporting the outer end of the bed frame. Such extension of the bed frame again tensions the springs 30, to a sufficient degree to steady or stay the structure and to yieldingly support the same from any outward movement, which movement, however, would be impossible in any event, owing to the toggle connections afforded between the respective brackets and toggle bars whereon the bed frame is supported on both the davenport frame and the forward edge of the seat frame.

When it is desired to close the davenport, the outer end of the bed frame is elevated, as shown in Fig. 4, and the bed frame is rolled upon the mattress and bedding, the legs 26, automatically swinging to closed position and the latching bar 27, projecting into position to engage the projection 28, on the bed frame section 8. Having folded the outer end of the bed frame into closed position, the pillows or other extra bedding, may be inserted in the box afforded by the seat frame and beneath the section 8, said section with the seat being rolled upwardly and inwardly, the draft of the springs very materially assisting this movement, inasmuch as such springs afford a balanced construction.

As the seat frame rises to the position shown in Fig. 3, the toggled connections between the same and the bed frame, and the davenport frame, brings the same inwardly and rearwardly, closing the seat frame upon the folded mattress frame, the respective toggled bars swinging the same eventually to the position shown in Fig. 2, with the bed frame section 8, lying flat against, or some-

what within the box afforded by the seat frame. Having pushed the folded bed frame, mattress and seat frame inwardly against the resistance of the springs, the 5 latch engages to hold the same positively closed against the draft of the springs, the entire structure, however, occupying a space within the davenport frame far below the normal level of the bed when in use.

10 From the construction described, it is evident that the latch bars 27, may be released by raising slightly upward on the leg 26, and drawing the same slightly outward sufficiently to retract the throat of the hook on the latch 27, from the pin 28. Ordinarily, 15 the frame construction is such that such upward pressure and outward contraction may be effected on either side of the bed or centrally, as preferred, with the result of unlatching both latch bars. If desired, however, 20 said latch bars may be so connected as to insure that the release of one will also release the other or the engagement of one will insure the engagement of the other.

25 Of course, it is to be understood that details of the construction may be varied. If desired, of course, a less number of folding sections may be provided in the bed frame, and other details of construction may be 30 varied through a wide range. I have shown but one (and that a preferred) construction embodying my invention. I therefore do not purpose limiting the patent on this application otherwise than necessitated by the 35 prior art.

I claim as my invention:

1. A davenport of the class described embracing a box frame, a seat pivotally supported at the forward edge of the box frame 40 to close thereon, a bed frame comprising a plurality of articulated sections pivotally connected with the box frame and the seat and adapted to roll outwardly in opening, springs disposed to elevate and support said bed frame in opening the same, automatically extensible legs on the seat for supporting the seat, automatically extensible legs at the outer end of the bed frame, and a 45 detent rigidly engaged on each of said last mentioned legs and adapted to rigidly engage one of the sections to lock the sections in closed position when the sections are folded inwardly.

2. A davenport of the class described embracing a box frame, an invertible seat, an upwardly projecting bracket secured to each end of the box frame, a link connecting each bracket with the forward and bottom edge of the seat, standards on the seat projecting 50 upwardly when the seat is inverted, a bent lever pivotally engaged on the box frame, a link connecting said seat standard with said bent lever, an articulated bed frame consisting of a plurality of sections supported on said standards and said bent le-

vers and adapted to be extended and supported thereby, automatically acting means for supporting the outer end of the bed frame when extended, a rigid detent acting automatically to engage one of said sections 70 to hold said articulated sections in closed relation when closing and to release the same when opening the bed frame.

3. A davenport of the class described embracing a box frame, a bed frame articulated to afford a plurality of sections and adapted together with the mattress thereon to fold from the outer end continuously inward, a rigid latch to bind adjacent sections of the bed frame in closed position, springs 80 disposed to yieldingly support the rolled up structure while lowering the same into the box frame, and to balance its weight when opening and a seat carrying said bed frame and affording in its open position a support therefor and in its closed position affording a seat for the davenport.

4. A device of the class described embracing a short davenport frame having a box frame, a seat to close thereon, an upwardly extending bracket on the front side of said box frame at each end thereof, a standard on the seat frame at each end thereof near the front edge, a link connecting the top of the bracket at each end of 95 the frame with the bottom of the standard, a bent lever pivoted on each end of the box frame near said bracket, a mattress frame constructed in outwardly opening articulated sections, the first of which is pivotally secured at about its middle on the bent lever, a second short mattress frame section 100 pivoted at its middle on the top of said standards, and a standard pivoted on the seat and to a third mattress frame section to support a part of the bed frame.

5. A davenport of the class described embracing a davenport frame, a box frame therein, an invertible seat, an upwardly projecting bracket on the box frame at each 110 front corner, a rigid standard on the bottom of the seat at each front corner, a link connecting the top of said bracket with the corresponding standard near its base, a bent lever pivotally engaged on the box frame near each bracket, a bar connecting said seat standard with said bent lever, an articulated sectional mattress having its first inner section near its middle pivotally secured on said bent levers, the second section pivotally engaged on said standard, a swinging standard connecting a third section at each end with said seat bottom, a swinging leg on each end of said seat bottom adapted to support said seat when extended, connected arms pivoted on the seat frame ends and links connecting one of said arms with the leg and the other with the swinging standard to actuate the same to support the outer end of the mattress frame when extended 125 130

and to close the legs when the mattress frame is folded inwardly.

6. A device of the class described embracing a davenport frame comprising a box frame, a seat pivotally supported at the forward edge of the box frame to close thereon, a mattress frame comprising a plurality of articulated sections pivotally connected with the box frame of the davenport frame and 10 with the seat and adapted to roll outwardly in opening the same, springs disposed to elevate and support said mattress frame in opening the same, a leg on the seat to support the seat from the floor, movable arms 15 on the seat bottom for supporting one of said mattress frame sections, a rod on the seat frame connected with each of said arms to operate the same simultaneously, an outer mattress frame section connected with said 20 last named mattress frame section and a leg at each end thereof acting to support the bed in horizontal position when extended.

7. A davenport of the class described embracing a davenport, a box frame therein, a 25 seat connected to the front of the box frame to close thereon, a mattress frame comprising a plurality of transversely articulated sections, a lever pivotally engaged near each front corner of the box frame and pivotally 30 engaged on the inner section to the mattress frame, standards rigidly secured on the under side the seat near its front and pivotally engaged at their upper ends on the second section of the mattress frame, a link connecting each standard with its corresponding lever intermediate their ends, a link pivotally supported on the seat bottom and pivotally engaged with a third mattress frame section, a swinging leg adapted to support 35 the seat at its outer edge when inverted, toggle bars pivotally engaged on the seat bottom and engaging said link and swinging leg and adapted to actuate both, the one to support the seat when turned outwardly, the 40 other to support the third section of the mattress frame, an outer mattress frame section connected to said third section, legs secured thereon and connections for projecting said legs downwardly when the mattress frame is 45 fully extended.

8. A five fold articulated mattress frame arranged in alternately long and short lengths, a davenport frame, a box frame therefor, brackets on said box frame, standards secured on the bottom of the seat at each end thereof and pivotally engaging the first pair of short mattress frame sections, a lever pivoted on the box frame at each end near the front and pivotally engaging the 55 first long mattress frame section in advance of the middle thereof, a bar connecting said lever and said standard, a link connecting the top of each bracket with the seat bottom, a swinging standard engaged at the rear side the seat, and pivotally engaging the 60

second long frame section, a swinging leg at each end of the seat bottom, linked connections with the bottom of the seat for simultaneously actuating said swinging standard and legs by the forward swing of the seat 70 when inverted to project said legs to supporting position and said standards to elevate and support its mattress frame section in a horizontal plane with the before-mentioned sections, legs pivotally engaged intermediate their ends near the outer end of the outer long section, links pivotally engaged near the middle of the adjacent short section and connected with the upper end of the legs and acting to project said legs to 75 supporting position when said outer long section is turned downwardly to a common plane, and means acting to exert inward tension on the mattress frame when extended.

9. A device of the class described embracing five articulated sections affording a mattress frame adapted to be folded inwardly from the outer end with its bedding, a box frame adapted to receive the same therein, a seat connected to the box frame, and adapted when inverted to act together with said box frame to support a part of the mattress frame elevated thereabove in a horizontal plane, legs on the outer mattress section, connections with an inner section of the mattress frame for automatically actuating the same in opening and in closing the device and a detent rigidly engaged on said outer legs and acting to rigidly engage an inner section to lock the same closed when the sections are folded inwardly.

10. A device of the class described comprising a bottom box frame and a seat box frame, each affording a receptacle, the one to receive therein the bed frame and mattress, the other to receive therein, when inverted, pillows and extra bedding, connections between said box frames acting to support thereon the mattress frame in extended and elevated position, automatically acting connections for swingingly connecting said box frames together and permitting the mattress frame to be folded from the outer end inwardly together with its mattress and bedding, an automatically extensible leg 115 carried at the outer end of the mattress frame, and a latching bar rigidly secured on each of said outer legs and acting automatically when the mattress frame and bedding are folded to rigidly engage the same in 120 folded position.

11. In a device of the class described two box frames, one affording the bottom portion of a davenport, the other affording the seat frame, linked connections swingingly connecting said box frames to permit said frame to be inverted outwardly, a mattress frame comprising five articulated sections, connections for supporting said articulated sections on said box frames, an automatic- 125

cally extensible leg at the rear side and end of the box seat frame, a bar connected on said seat frame and acting to support one of the mattress frame sections, means act-
5 ing to elevate the mattress frame thereon when the seat frame is inverted, an automatically extensible leg on the outermost section, and a latching bar rigidly engaged on said leg and acting to engage said mat-
10 tress in folded relation when closed.

12. A device of the class described embracing a davenport frame having a box frame, a seat to close thereon, a bracket on each end of said box frame, a standard on
15 each end of the seat frame, links connecting the top of said brackets with the bottom of the corresponding standards, a lever pivoted on the box frame near each bracket, a mattress frame constructed in outwardly open-
20 ing articulated sections, the first of which is pivotally secured at about its middle on said levers, a second short mattress frame section pivoted at its middle on the top of said standards, a standard pivoted on the seat
25 and to a third mattress frame section to support a part of the bed frame, and a leg pivoted to the seat end and acting to support said third frame section thereon when the bed is opened.

30 13. A davenport of the class described embracing a davenport frame, a box frame therein, an invertible seat, an upwardly projecting bracket on each end of the box bottom of the frame, a rigid standard on the
35 bottom of the seat, a link connecting the top of each bracket with the base of the corresponding standard, a bent lever pivotally engaged on the box frame near each bracket, a link connecting said seat standard with
40 said bent lever, an articulated sectional mattress having the inner section thereof pivotally secured near its middle on said bent levers, the second section pivotally engaged on said standard, links connecting a third
45 section with said seat bottom and legs adapted to support a part of the outer end of the mattress frame when extended.

14. A five fold articulated mattress frame arranged in alternately long and short
50 lengths, a davenport frame, a box frame therefor, a standard secured at each end of the bottom of the seat and pivotally engag-
55 ing the first pair of short mattress frame sections, a lever pivoted on each end of the
60 box frame and pivotally engaging the first long mattress frame section, links connect-
65 ing said levers to the corresponding stand-
ards, a link pivotally engaged at each end of, and at the near side of the seat, said link
pivotally engaging the second long frame section, a swinging leg on each end of said seat, and means connected with the bottom of the seat for simultaneously actuating said swinging legs and links with the movement
65 of the seat.

15. A davenport of the class described embracing a bottom frame, a seat box frame, connections between said box frames and acting to support thereon the mattress frame in extended and elevated position, connec-
70 tions for swingingly connecting said box frames together and permitting the mattress frame to be folded from the outer end in-
wardly together with its mattress and bed-
ding, automatically extensible legs carried
75 at the outer end of the mattress frame, and a latching bar rigidly secured on each of
80 said outer legs and acting automatically when the mattress frame and bedding are folded, to rigidly engage the same in folded position.

16. A davenport of the class described embr-
acing a davenport frame, a box frame therefor, a bed frame articulated to afford a plurality of sections and adapted together
85 with the mattress thereon to fold from the outer end continuously inward, an automatically acting latch adapted to bind the bed frame in closed position, springs disposed to yieldingly support the rolled up structure
90 while lowering the same into the box frame, and to balance its weight when opening, and a box seat affording a receptacle and attached to said bed frame and affording in
95 its open position a support therefor and in its closed position affording a seat for the davenport.

17. In a sofa or davenport bed, in combi-
nation, a folding bed section, a leg therefor
100 hinged thereto, said leg provided with a sec-
tion latching extension, and means actuated by said folding bed section to cause said leg and latching extension to automatically assume operable position when the bed section is respectively opened and closed.

105 18. A sofa bedstead comprising a main frame, end pieces and a back piece for said frame, a seat normally supported between said end pieces, a plurality of movable bed bottom sections connected to said seat and supported therewith by said main frame, the outermost of said sections being reversible toward and pivoted to the adjacent section, a leg pivoted upon and at the outer end of aforesaid section, a section locking latch device operated by the folding movement of said pivoted leg, as set forth.

19. In a sofa bed, the combination of a stationary frame, a couch seat which is hinged to said frame and is adapted to be inverted in front thereof, and a folding bed bottom independent of said couch frame and seat having a frame comprising connected inner, outer and intermediate sections ar-
120 ranged to fold with said outer section be-
tween said intermediate and inner sections, said intermediate section being mounted on the underside of said couch seat and sup-
125 ported above the same when the seat is in-
verted, and extending substantially from
130

front to rear of said couch seat, means movably supporting the inner edge of said inner section from the stationary couch frame, and supporting means for said outer section, substantially as set forth.

20. In a sofa bed, the combination of a stationary frame, a couch seat which is hinged to said frame and is adapted to be inverted in front thereof, and a folding bed bottom having a frame comprising connected inner, outer and intermediate sections arranged to fold with said outer section between said intermediate and inner sections, said intermediate section being mounted on the underside of the couch seat to move relatively thereto and being supported above the same when the seat is inverted, supporting means which connect said inner section to said stationary frame and permit said inner section to rise and fall when the couch seat is swung from and to its normal position, and supporting means for said outer section, substantially as set forth.
21. In a sofa bed, the combination of a stationary frame, a couch seat which is hinged to said frame and is adapted to be inverted in front thereof, and a folding bed bottom having a frame comprising connected inner, outer and intermediate main sections and a spacing section between said outer and intermediate sections arranged to fold with said outer section between said intermediate and inner sections, said inter-

mediate section being mounted on the underside of said couch seat and supported above the same when the seat is inverted, movable supporting means connecting said inner section with the stationary frame, and supporting means for said outer section, substantially as set forth.

22. In a sofa bed, the combination of a stationary frame, a couch seat which is hinged to said frame and is adapted to be inverted, a folding bed bottom which has a rectangular frame that is complete in itself independently of said couch frame and seat and which is adapted to be folded with the outer end portion thereof between the intermediate and inner end portions thereof, said intermediate portion being mounted on the underside of said couch seat and supported above the same when the seat is inverted, and movable supporting means connecting said inner end portion of the bed bottom with the stationary couch frame and coöperating with said intermediate portion of the bed bottom to support said inner end portion, substantially as set forth.

In testimony whereof I have hereunto subscribed my name in the presence of two 60 subscribing witnesses.

PETER E. KROEHLER.

Witnesses:

C. W. HILLS,
LAWRENCE REIBSTEIN.
